OUTDOOR CANOPY

Charles W. Lemen, Springfield, Ohio, assignor to The Springfield Tent & Awning Company, Springfield, Ohio, a corporation of Ohio

Application July 23, 1954, Serial No. 445,410

5 Claims. (Cl. 135—5)

This invention relates to an outdoor canopy of economical and sturdy construction and which finds particular use on golf courses, lawns and swimming pools where resistance to wind, for example, is of importance.

The invention particularly contemplates the provision of an outdoor canopy in which the canopy cover and the frame therefor is tiltably mounted and readily securable in the tilted position for the achievement of maximum shade from sun up to sun down.

The invention further contemplates an outdoor canopy which is readily manipulated and is of low cost, simplified mechanical construction.

Another object of the invention is the provision of an outdoor canopy in which the canopy cover is securely and simply affixed to the tilttable canopy frame.

An important object of the invention is the provision of an outdoor canopy having a tilttable canopy cover provided with tilting means which are not adversely affected corrosion-wise.

These and other objects and advantages will become apparent from the following detailed description and accompanying drawings wherein:

Figure 1 is a perspective view of the outdoor canopy of the invention;

Figure 2 is a sectional view taken on line 2—2 of Figure 1;

Figure 3 is an enlarged fragmentary view of a portion of the structure of Figure 2;

Figure 4 is a fragmentary view of the right hand portion of the structure of Figure 1;

Figure 5 is a view taken on line 5—5 of Figure 4;

Figure 6 is a perspective fragmentary view of a portion of the structure of Figure 4;

Figure 7 is a perspective view of a central portion of the canopy;

Figure 8 is a sectional view taken on line 8—8 of Figure 7 particularly illustrating the means for retaining the canopy cover securely;

Figure 9 is a perspective view of a portion of the canopy cover;

Figure 10 is a view taken on line 10—10 of Figure 1;

Figure 11 is a perspective view of a further embodiment of the structure of invention illustrating other retaining means for the canopy cover; and

Figure 12 is a bottom plan view of the structure of Figure 11.

Referring to the drawings there is shown in Figure 1 a positioned outdoor canopy and provided therefor at 1, 3 are foundations in the form of cylindrical concrete blocks. Mounted in these blocks are spaced tubular stanchions 5, 7 in the form of pipes, the upper ends of which support therebetween a frame of box-like shape indicated generally at 9. Stretched over the frame 9 and supported thereby is a canopy cover 11.

The box-like frame is pivotally supported by means provided at the upper ends of the stanchions 5, 7 and the frame 9 is constituted by horizontally extending support members 13, 15, each of substantially rectangular

2

shape and spaced apart vertically by a plurality of metal webs welded thereto and extending therebetween as at 17 (Figure 1). Also welded between the frames at opposed longitudinal ends of the canopy as at 19, 20 (Figures 2 and 3) are end plates to which are secured the means for effecting pivotal movement of the box-like frame 9 as noted more particularly hereinafter.

Referring now specifically to Figures 1—3, inclusive, it will be noted that the upper end of the stanchion 7 is provided with an elbow 21 which is threaded at 23 to receive a plug 25 having a reduced portion 27 into which bolt 29 is screwed.

As shown most clearly in Figure 3 the end plate 20 is provided with an aperture through which reduced portion 27 of plug 25 passes freely, the aperture being of a sufficient size to permit the plate 20 to rotate about the reduced portion 27. The reduced portion 27 is suitably of a cross sectional shape which permits rotatable movement of the plate 20 thereof about portion 27 and may suitably be 4, 5 or 6 sided, or even circular, and the portion functions to support the frame 9 rotatably; thus the portion 27 constitutes a bearing for the frame.

A washer 31 is provided between the reduced portion 27 and the head of the bolt 29 and is spaced slightly from the end plate 20 (Figure 2) in the operative position of the structure, and serves to retain the plate 20 against lateral movement.

The arrangement of the opposite ends of the frame is identical and accordingly the plate 19 (Figure 4) is pivotally mounted with respect to elbow 22 as described in connection with Figures 2 and 3.

Referring now to Figures 4—6, inclusive, the plate 19 is of lesser thickness than the diameter of the tubular pipe members constituting the frames 13, 15, and accordingly plate 19 is suitably provided with metallic pads 33 welded thereto, and to these pads there are attached by screws 35 bar members 37 of semicircular shape.

Referring now to Figure 5 the stanchion 5 is provided with a J-bolt 39 the shank 41 of which extends through opposed apertures of the stanchion. The shank 41 is threaded at 43 and receives the nut portion 45 of a handle 47.

The remote end of the J-bolt at 49 extends into an upper aperture (Figure 5) of the stanchion vertically spaced above the shank of the J-bolt, and the base 51 of the J together with the stanchion 5 encompasses therebetween a portion of the bar member 37 and securely retains the bar member. Thus the box-like frame 9 is securable in pivotal position with respect to the stanchions 5, 7 by adjustment of bar member 37 with respect to J bolt. It will be understood that the opposed ends of the box-like frame with respect to the mounting for pivotal movement of the frame are identical, and that the handle 48 and the bar 38 (Figure 1) correspond to the handle 47 and the bar 37.

55 To pivotally move the box frame it is simply necessary to partially unthread the handles 47, 48 on their J-bolts, which loosens the J-bolts from the bar members 37, 38, respectively, and the box-like frame is then merely pushed or pulled into position pivotally on the reduced 60 bearing portions of the plugs, whereafter the handle 47 is again threaded back onto the shanks of the particular J-bolt and bears against the corresponding stanchion to securely draw the associated bar member against the stanchion. This operation is of course performed at each 65 end of the structure to permit rotation and securing of the frame which supports the canopy.

Referring now more specifically to Figures 2 and 7—9, inclusive, it will be noted that the canopy 11 comprises a first depending decorative portion 53 and a second reinforcing strip portion 55 (Figure 9) suitably sewn to the cover 11. This strip 55 extends completely around the canopy and itself has depending pocket members 57 sewn

thereto. Preferably four pocket members 57 are provided, two of which extend over a major portion of the length of the canopy, and the other two of which are U-shaped and extend around the ends of the canopy. One of these end U-shaped portions is indicated at 57 in Figure 2.

Positioned in these pocket members 57 are metal rods 59 and when the canopy is positioned, as shown most clearly in Figure 8, J-bolts 61 suitably provided through the spaced webs 17 have the hooked portion thereof secured about the rods 59, while the shank of the J-bolt is retained in position by nuts 63 threaded on the shank.

Referring now to Figure 7, it will be noted that the support member 13 is continuous and constituted of pipe members connected together by a suitable nipple at 65. Similarly the upper frame 15 consists of pipe members suitably joined by connectors 67, and the connectors 67 are provided with transverse members 69 which extend laterally of the canopy 11 (Figure 1) and supports the same.

To reduce wear on the canvas canopy the canopy is itself reinforced at 71 as most clearly shown in Figures 1, 7 and 10. The depending strips of the canvas, as shown at 72 assist in retaining the cover 11 and the stiffening member 69 positioned together.

Referring now to Figures 11 and 12 wherein a further embodiment of one arrangement of the invention is shown, there is illustrated in Figure 11 a canopy 11' which is supported on a box-like frame constituted of vertically spaced frame members 13', 15', spaced apart by webs 17' welded therebetween. In this instance the canopy 11' has sewn thereto as at 73 a depending portion which is suitably provided with a lacing 75 for engagement with the pipes constituting the frame member 15'.

Also in this instance the frame 15' has suitably welded thereto at 77 a small plate 79 through which a nut and bolt indicated generally at 81 pass and to which bolt a transverse stiffening member 69' is secured. Thus the canopy 11' is supported by the frame indicated generally at 9'.

It will thus be noted that there has been described a rugged structural arrangement for an outdoor canopy which is of simple mechanical components, economical to produce and extremely serviceable.

It will be understood that this invention is susceptible to modification in order to adapt it to different usages and conditions and accordingly, it is desired to comprehend such modifications within this invention as may fall within the scope of the appended claims.

I claim:

1. In an outdoor canopy, in combination, a frame comprised of vertically spaced canopy cover support members, means, including spaced vertically extending metal web means secured to the members and spacing the members apart vertically, a canopy cover extending across the frame and having a depending pocket member terminating vertically between the support members, rod means extending horizontally in the pocket member, and hook means extending from the web means about the pocket member and rod means securely retaining the latter.

2. In an outdoor canopy, in combination, a frame comprised of vertically spaced canopy cover support members, web means secured to the members, extending vertically between the members and spacing the members

vertically, means comprising J-bolts extending through and supported by the web means, a canopy cover extending over the frame and having a portion depending therebelow, pocket members of the canopy cover between the frame and depending portion of the canopy cover, and rod means in the pocket members extending substantially horizontally and retained by the hook portions of the J-bolts which engage about the pocket members.

3. In combination, in an outdoor canopy, a frame comprising vertically spaced canopy cover support members, plates oppositely disposed in parallel relation and secured to the support members and positioned between the members spacing the same vertically, stanchions extending in planes parallel to the plates, and means pivotally supporting the frame on the stanchions, said means including bearing means extending from and secured to the stanchions and pivotally supporting the plates, the plates each having an arcuate member depending therefrom parallel and adjacent to a stanchion, and securing means for the arcuate members passing through each stanchion supported thereby and releasably secured to an arcuate member retaining the same in position against a stanchion.

4. In an outdoor canopy, in combination, spaced stanchions each having at an upper extremity thereof an elbow, a frame supported pivotally with respect to the stanchions, the frame comprising vertically spaced canopy cover support members having parallel vertically extending plates oppositely disposed and secured to the plates therebetween spacing the members vertically, each plate having therethrough an aperture, and bearing means supported by the elbows disposed through each aperture pivotally supporting a plate, and means for securing the plates in position with respect to the stanchions, said latter means comprising semi-circular rod-like members depending from each plate at opposite ends and on either side of the aperture and bearing means and extending underneath the bearing means, the stanchions each having J-bolts passing therethrough carried thereby and extending about the rod-like members retaining the same.

5. The combination, in an outdoor canopy, of a frame and a canopy cover secured thereover, the frame comprising vertically spaced tubular canopy cover support members each of which comprises tubular rods connected together forming an endless support member, the members having web means welded to the members and extending vertically therebetween spacing the members vertically, the canopy cover having a portion extending downwardly and outwardly of the lower of the support members and having spaced pocket members depending freely therearound between the canopy cover and the web means, the pocket members having therein rods, and the web means having transversely therethrough supported thereby J-bolts the hook portions of which J-bolts engage about the pocket members and rods and retain the pocket members inwardly of said canopy portion.
